UNITED STATES PATENT OFFICE.

ROBERT J. WOOD, OF SPRING HILL, WEST VIRGINIA, ASSIGNOR TO GOODMAN MANUFACTURING COMPANY, OF CHICAGO, ILLINOIS, A CORPORATION OF ILLINOIS.

SCRAPER LOADING APPARATUS.

Application filed March 17, 1923, Serial No. 625,752. Renewed September 7, 1926.

This invention relates to improvements in scraper loading apparatus, particularly adapted for gathering and transporting loose material in mines, and has for its principal object to produce an apparatus of the class described capable of gathering and transporting loose material, such as coal at the working face of a mine room or entry and transporting the material to another point 10 to be loaded in mine cars.

My invention may best be understood by reference to the drawings illustrating one form in which it may be embodied, in which—

15 Figure 1 is a plan view of a typical installation of my apparatus in a mine, and including as a cooperating element a coal mining machine of the overcutting or slabbing type.

20 Figure 2 is a side view of an overcutting or slabbing machine showing my improved apparatus applied thereto.

25 Figure 3 is an enlarged detail showing the scraper and a cooperating bearing device, with parts broken away.

Figure 4 is a sectional view taken on line 4—4 of Figure 3.

Figure 5 is a sectional view taken on line 5—5 of Figure 3.

30 Figure 6 is a sectional view taken on line 6—6 of Figure 3.

Figure 7 is a sectional view taken on line 7—7 of Figure 3.

35 Figure 8 is a detailed plan view of a rope deflecting arm used in connection with my apparatus.

Figure 9 is a transverse section of the arm shown in Figure 8.

40 Figures 10—11—12 and 13 are diagrammatic views of the apparatus illustrated in Figure 1 and show the scraper in various positions of operation thereof.

45 In order to illustrate the construction and operation of my invention the accompanying drawings show a typical installation in a coal mine. Figure 1 and the diagrams in Figures 10 to 13, both inclusive, show a mine room or entry 10, being extended laterally from a main haulage passage 11 in which are haulage tracks 12, 12 for movement of mine cars 13, 13, therewith. In the mining operation illustrated the coal is removed by advancing the working face indicated at 15 at the far end of the 50 room 10, this advancing being done by any

approved mining methods as for instance, by cutting a kerf across the working face 15 by means of a kerf cutting mining machine, and thereafter blasting or breaking down the portion of the working face so as to deposit the coal in a loose pile as indicated at 16 adjacent the working face. The devices for undercutting or blasting need not be shown or described in detail, as they form no part of the present invention, excepting that under many conditions of mining it is desirable to cut a kerf in the working face by means of a machine of the slabbing or overcutting type, indicated at 17, and when such a machine is used for this purpose it may be conveniently used as a part of the improved apparatus which embodies my invention. That is to say, a machine of the slabbing type is particularly adaptable for use as a pivotal turning device in connection 70 with my improved scraper apparatus, although so far as the broad features of my invention are concerned other forms of turning devices may be used, as will hereinafter more fully appear.

55 As herein shown the scraper apparatus comprises a scraper 20, having a head rope 21 and a tail rope 22 connected therewith to move the scraper reciprocably. The ropes are operably connected with a suitable power controlling device, which in the form shown comprises winding drums 23 and 24, mounted on the base frame 26 of the mining machine 17 and connected with ropes 21 and 22, respectively. These winding drums are arranged to be power driven in any suitable manner as for instance, by means of a motor 35 which is the same motor used for operating the cutting machine. The operating and controlling devices for the drums 23 and 24 need not be shown in detail as they form no part of the present invention, and may be of any approved form and construction, including braking devices, as are commonly used for the operation and control 100 of draft operated scrapers.

60 As herein shown the mining machine 17 is mounted on tracks 12^a branching from the main track 12 into the room or entry 10, and arranged to guide and support the cutting machine 17 while it is in position to cut a kerf or kerfs in the usual manner. The cutting machine is provided with a cutting element 30 of any approved type for cutting a kerf, said cutting element being mounted 105 110

on a turntable 33 rotatably mounted on the base frame 26 and movable vertically respective thereto by suitable means such as pinions 31, 31 on the cutting element 30 working in racks 32, 32 extending upwardly from the turntable 33. The turntable is arranged to be swung angularly during the cutting operation by suitable power mechanism which need not be described in detail, it being understood that the scraper apparatus is used in connection with the mining machine shown, only after the cutting operation has been completed, and the mechanical devices used for this cutting operation are inoperative.

Referring now more particularly to the details of the scraper apparatus, it will be seen from Figures 1 and 2 that the scraper 20 is adapted at times to have lateral engagement with a curved bearing member 25. This bearing member is connected to a supporting beam pivotally fixed in the mine so that said beam will be swung angularly during the loading operation. In the preferred form shown this beam comprises the cutter element 30 of the cutting machine 17 which cutting element is movable angularly respective to the base frame 26 of the machine as has been hereinabove described. The bearing member 25 is detachably connected adjacent the outer end of the cutting element 30 so as to permit the removal thereof while said cutting element is being used for cutting a kerf. Any suitable means may be provided for affording this detachable connection, as for instance, as shown in detail in Figures 6 and 7, which show a stud 36 extending upwardly from the central portion of the bearing arm 25 through the cutting element 30 and detachably secured thereto by suitable means, such as a bolt 37, extending coaxially through the stud 36, and provided with a nut 38 engaging the upper face of the cutting element 30. The bearing arm 25 has limited pivotal movement respective to the cutting element. For this purpose the upper and lower plates 39 and 40 of the bearing arm 25 are journaled on the stud 36. A plate 41 adapted to engage the under face of the cutting element 30 supports stud 36, and when in position, extends on opposite sides of said cutting element to provide bearing for the upper plate 39 of the bearing arm 25. A supporting bracket 42 is also connected between the plate 41 and the lower end of the stud 36, as shown.

A bearing roller 43 is rotatably mounted on the central stud 36 in position to be engaged by the scraper 20 and tail line 22. A similar bearing roller 44 is mounted at the forward end of the arm 25 in position to form a bearing for the head line 21 and the scraper. A sheave 45 is mounted at the rear end of the arm 25 in position to be engaged

by the tail line 22, and is preferably provided with a guide 46 carried on the arm 25 so that the tail line passes therethrough and is retained on said sheave.

The scraper is adapted to have lateral bearing engagement with the outer face of the bearing arm 25 as shown in detail in Figure 3. Means are provided for connecting the scraper and the bearing arm when in this position so that the scraper and bearing arm, together with the beam 30, will be moved bodily by the draft means and swung pivotally about the turntable 33. I have shown one means which may be used for this purpose, which comprises a projection 50 adjacent the forward end of the rocking arm 25 in position to engage the forward upright margin 51 on the inner or bearing side 52 of the scraper. Another projection or stop 53 is provided adjacent the rear end of the scraper in position to be engaged by a stop 54 on the scraper. By means of these coacting stops 50, 51, and 53, 54, the scraper will be automatically connected with the bearing arm 25 when it is moved into lateral engagement therewith, as shown in Figure 3. Further means are provided for disconnecting the scraper from the bearing arm when the scraper, together with the bearing arm and beam are moved forwardly to a predetermined point as for instance, a direction changing device or deflector 55 is fixed to the mine floor by suitable means, such as mine jacks of the ordinary type, at a point where it is desired to limit the swinging movement of the beam 30. (See Figure 12.) The forward end of the bearing arm 25 is provided with an outwardly facing cam member, indicated at 56, which is adapted to engage the direction changing device 55 and cause the forward end of the bearing arm 25 to swing inwardly, thereby releasing the forward edge 51 of the scraper from the projection 50 on the bearing arm.

A direction changing device 60 is preferably positioned in advance of the pivotal connection of the beam 30, in order to provide a large angle of draft by means of the head or tail lines when the said beam is in extreme positions at one side or the other of the base frame 26. In the form shown, this direction changing device comprises a vertically disposed roller 65, mounted on the end of a support 61, telescopically connected under the frame 26 and adjustable to various lengths by means of a locking pin 63 adapted to fit in one of a series of holes 64, 64 in said support, as shown in Figures 8 and 9. The roller 65 is provided with a hinged pick-up member 66, adapted to engage the ground, so as to deflect the draft ropes upwardly to the roller in case they are temporarily slackened or dropped to the mine floor.

The use and operation of my device above

described will be understood by referring to the diagrams shown in Figures 10 to 13, inclusive. In Figure 10 the apparatus is shown in position to start the loading operation adjacent the working face 15 of a mine room or entry, with the loose material deposited in a broken state adjacent said working face. The inner margin or toe of the pile of loose material is indicated at 16. The bearing arm 25 is shown in position adjacent the outer end of the beam 30. In case a cutting machine such as described above is used it may first be necessary to change the vertical position of the cutting element which comprises the beam 30, it being understood that machines of this type are usually provided with an elevating device for the cutting element so as to cut a kerf at various heights. When the bearing arm 25 is connected for use with a scraper, however, this cutting element is adjusted to the proper height for this purpose. The draft lines 21 and 22 are trained so as to be movable about the bearing arm 25 and are also trained about suitably arranged direction changing devices as for instance, the head line 21 is trained about guide sheaves 68 and 69 in the haulage entry 11, from thence to the fixed deflector 55 and to the roller 65 on the projecting support 61. The roller 65 is positioned within the path of movement of the arm 25. The tail line is trained about a fixed guide 57 in the room 10, and another sheave 58 carried on the rear end of the machine 17. In the position shown in Figure 10, the scraper is shown adjacent the right hand rib or wall 15 in the initial or starting position for gathering a load. The tension on the tail rope is released to unwind freely from its drum 24 and tension is put on the head rope 21 by winding in on the drum 23. The forward margin 51 of the scraper is engaged with the stop 50 on the bearing arm 25 so as to cause the bearing arm and beam 30 to be swung angularly and describe an arc indicated progressively in dotted lines in Figures 11 and 12. It will be noted that during this movement of the beam 30, the draft on the scraper and bearing arm is in a general direction at less than a right angle with respect to the beam, and this angular draft serves to rock the forward end of the pivoted bearing arm 25 inwardly and the opposite or rear end thereof outwardly, so as to trust the scraper outwardly to follow a relatively long radius as it moves about with the beam and digs into the loose material to gather the same. The angular movement of the scraper is continued until the cam surface 56 at the forward end of the pivoted arm 25 engages the fixed deflector 55 as shown in Figure 12. In this position the forward end of said arm is swung inwardly so as to disengage the front edge of the scraper 51 from the stop 50 on said arm, thereby disconnecting the scraper from the bearing arm and permitting it to pass onward about the outer side of the deflector 55. The movement of beam 30 and arm 25 is thus limited, and they maintain the position shown in Figure 12 while the scraper moves forwardly to a point of discharge, as for instance, to the loading chute 19, extending over the edge of one of the cars 13, which is loaded in the usual manner. Movement of the scraper is then reversed by changing the power connections from the winding drum 23 to the winding drum 24, thus releasing the head rope 21 and pulling on the tail rope 22. The scraper is then moved rearwardly about the deflector 55 into engagement with a bearing arm 25, and is automatically connected thereto by means of the coacting stops 53 and 54 so that the bearing member 25 and beam 30 is returned angularly toward the initial position, as indicated in Figure 13. It will be observed from this figure that the pull on the tail rope is generally in a direction at less than a right angle with respect to the beam 30, so as to rock the bearing member 25 in the reverse direction, with the scraper 20 drawn inwardly whereby the scraper follows about a radius relatively shorter than that described by the scraper during its forward movement. The scraper thus avoids contact with the toe of the pile during its rearward angular movement. After the scraper has reached the limit of angular movement rearwardly, as shown in Figures 1 and 10, it is in position to start another forward loading movement. As the loading operation continues, the machine 17 is advanced toward the working face until all the loose material is loaded out.

While I have shown and described one form in which my invention may be embodied, it will be understood that the construction and arrangement of the various parts, and the uses to which the apparatus may be put, may vary widely without departing from the scope of my invention. Furthermore, although I have shown and described a mining machine of the overcutting or slabbing type as a convenient part of the apparatus, it will be understood that so far as the broader features of my invention are concerned, other forms of pivotally swinging beams may be substituted therefor, if desired. I do not, therefore, wish to be understood as limiting myself to the details of construction herein shown and described, excepting in so far as specifically defined in the appended claims.

I claim as my invention:

1. In a scraper apparatus, in combination with a base, a projecting beam movable angularly respective to said base, a rocking

member on said beam, a scraper, and draft means for reciprocably moving said scraper extending about said rocking member whereby said scraper is movable into lateral engagement with said rocking member during a portion of its reciprocable movement.

2. In a scraper apparatus, a scraper, a head line and a tail line connected therewith for moving the same reciprocably, a base, a projecting beam pivotally connected with said base, a bearing member carried by said beam, and means on said bearing member coacting with said scraper to detachably engage the latter during a portion of the reciprocable movement thereof.

3. In a scraper apparatus, a base, having a projecting beam movable angularly respective thereto, a rocking member pivotally connected adjacent the outer end of said beam and extending in a general direction transversely of the longitudinal axis of said beam, a scraper adapted to be detachably connected with said rocking member while in lateral engagement therewith, and draft means extending about said rocking member for moving said scraper reciprocably, whereby the scraper is swung pivotally about said base during a portion of its reciprocable movement.

4. In a scraper apparatus, a base, a projecting beam pivotally connected with said base, a rocking member carried by said beam, a scraper having draft lines extend-

ing about said rocking member for moving the scraper reciprocably, means coacting with said scraper to detachably connect the same in lateral supporting engagement with said rocking member during a portion of the reciprocable movement of said scraper, and a tripping device for said rocking member operable automatically to release said scraper from connection therewith.

5. In a scraper apparatus, in combination with a scraper having draft means for reciprocably moving it, a base, a projecting beam movably angularly respective to said base, a rocking member on said beam adapted to have lateral engagement with said scraper during a portion of its reciprocable movement, and means on said rocking member coacting with said scraper whereby said beam and scraper are bodily moved angularly by said draft means.

6. In a scraper apparatus, in combination with a movable base having an angularly movable projecting beam, a rocking member pivotally connected adjacent the outer end of said beam, a scraper having cooperative engagement with said rocking member, draft means for reciprocably moving said scraper, direction changing devices for said draft means, and controlling devices for said draft means mounted on said base.

Signed at Chicago, in the county of Cook, and State of Illinois, this 28th day of February, 1923.

ROBERT J. WOOD.
